Inventor

ANTHONY NARDONE.

Watson E. Coleman
Attorney

UNITED STATES PATENT OFFICE.

ANTHONY NARDONE, OF WILKES-BARRE, PENNSYLVANIA.

TROUSERS.

Application filed November 11, 1922. Serial No. 600,280.

To all whom it may concern:

Be it known that I, ANTHONY NARDONE, a citizen of the United States, residing at Wilkes-Barre, in the county of Luzerne and State of Pennsylvania, have invented certain new and useful Improvements in Trousers, of which the following is a specification, reference being had to the accompanying drawings.

10 This invention relates to certain improvements in trousers and it is an object of the invention to provide trousers constructed in a novel and improved manner whereby the waist line may be expanded or contracted 15 as may be required without destroying the balance of the trousers.

Furthermore it is an object of the invention to provide trousers constructed in a novel and improved manner wherein the 20 side pockets, upon alteration at the waist line, are at the same position as before such alteration.

An additional object of the invention is to provide trousers constructed in a novel 25 and improved manner wherein the side seams are adapted to provide means for altering the waist line of the trousers in a manner to effect shrinking or enlarging together with a lining for holding the seams 30 in a flattened condition so that the trousers adjacent the seams are prevented from becoming bulging or otherwise unsightly or ungainly.

The invention consists in the details of 35 construction and in the combination and arrangement of the several parts of my improved trousers whereby certain important advantages are attained and the device rendered simpler, less expensive and otherwise more convenient and advantageous for 40 use, as will be hereinafter more fully set forth.

The novel features of my invention will hereinafter be definitely claimed.

45 In order that my invention may be the better understood, I will now proceed to describe the same with reference to the accompanying drawings, wherein:

Figure 1 is a fragmentary view in perspective illustrating trousers constructed in accordance with an embodiment of my invention; and

50 Figure 2 is an enlarged fragmentary sectional view taken substantially on the line 2—2 of Figure 1.

As disclosed in the accompanying drawings—

ings, A denotes the upper portions of the leg sections of trousers connected by the side seams 1 and are rear seam 2. The seams 1 of the upper portions of the leg sections 60 embody folds 3, the folds 3 of each of the rear sections being relatively wide so that the folds of the rear sections may be employed in contracting or expanding the waist portion of the trousers without throwing 65 the trousers out of balance.

Each of the side seams 1 adjacent the waist line of the trousers and for a desired distance therealong is interrupted or open as at 4 to provide an entrance to the pocket 70 5, said pocket 5 being carried entirely by a front section whereby as the trousers contract or expand the position of the pocket is not affected.

The pocket has associated therewith the 75 trimmings or facings 6 and one of said trimmings or facings is secured to and overlies the inside face of the inner wall of the pocket, said facing having its outer marginal portion secured to the trousers, such 80 securing being comprised in the side seam 1 connecting the front and rear sections of the trousers. The free marginal portion of the outer wall of the pocket, which is herein disclosed as comprising the second 85 facing or trimming 6, is secured to the front section of the trousers. By this arrangement the pocket is secured entirely to the front section whereby the desired adjustment of the trousers at the waist line may be effected 90 without the necessity of interfering in any way with the applied pocket or in other words the applied pocket offers no hindrance or obstruction to the required adjustment of the trousers at the waist line. 95

When it is desired to contract or expand the waist line of the trousers or to effect a shrinking or enlarging as referred to in shop terms, the operator need only cut the seams 1 and then adjust the folds or turns 100 3 of the rear sections as may be required in order to accomplish the desired fit.

By this operation it will be particularly noted that the side pockets are not affected in any way so that after the side seams 105 have been resewed the balance of the trousers is maintained due to the fact that the side pockets are not moved forwardly or rearwardly with respect to the side seams.

7 denotes a waist band or lining associated with each section of the trousers and it is to be particularly noted that no

one of the bands 7 laps or extends across a seam 1 but does overlie a turn or fold 3 of a seam 1 comprised in the trouser section to which the band is applied. This 5 structure is particularly illustrated in the accompanying drawings and where it will be noted that each of the waist band sections or linings serves effectually to maintain the folds or turns 3 in a flattened condition so that the trousers adjacent the 10 seams are prevented from bulging or otherwise becoming unsightly or ungainly. Effecting an alternation it is to be noted that the band or lining 7 stitched to the fold 15 or turn 3 of the rear section will be loosened but this only necessitates a further operation requiring but little time and labor.

From the foregoing description it is thought to be obvious that trousers constructed in accordance with my invention 20 are particularly well adapted for use by reason of the convenience and facility with which they may be assembled and operated, and it will also be obvious that my invention

tion is susceptible of some change and modification without departing from the principles and spirit thereof and for this reason I do not wish to be understood as limiting myself to the precise arrangement and formation of the several parts herein shown 25 in carrying out my invention in practice except as hereinafter claimed.

I claim:

In combination with a front section and a rear section of trousers and a side seam 35 connecting the same, a pocket, a facing secured to and overlying the inside face of the inner wall of the pocket, said facing having its outer marginal portion secured to the trousers, such securement being comprised in the side seam connecting the said sections, the free marginal portion of the outer wall of the pocket being secured to the front section of the trousers, said pocket being secured entirely to the front section. 40 45

In testimony whereof I hereunto affix my signature.

ANTHONY NARDONE.
